UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

TANK-CAR.

1,097,928.

Specification of Letters Patent. Patented May 26, 1914.

Application filed December 30, 1910. Serial No. 600,016.

To all whom it may concern:

Be it known that I, ALLEN E. OSTRANDER, residing at Ridgewood, Bergen county, New Jersey, and being a citizen of the United States, have invented certain new and useful Improvements in Tank-Cars, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a side elevational view of a tank car constructed in accordance with my invention, parts of said car being broken away and illustrated diagrammatically. Fig. 2 is an enlarged detail 20 central longitudinal sectional view of one of the end portions of the underframe structure shown in Fig. 1. Fig. 3 is a top plan view of the parts shown in Fig. 2, the tank being removed. Fig. 4 is a vertical transverse sectional view taken on the line 4—4 of Fig. 3, looking in the direction of the arrows and 25 showing the tank in place. Fig. 5 is a vertical transverse sectional view taken on the line 5—5 of Fig. 3, looking in the direction of the arrows and showing the tank in place, and Fig. 6 is a diagrammatic illustration of 30 a modified form of the invention.

The invention relates to means for anchoring independently constructed bodies of cars against longitudinal, or excessive longitudinal movement relative to the sustaining underframing thereof, at the same time so constructing and combining the respective parts 40 of the underframe and the car body and the anchor for the car body as to permit said car body to be readily removable from said underframe for repairs or renewal.

The invention is particularly applicable to tank cars, in which a cylindrical metal tank is mounted on an underframe comprising 45 principal center sills adapted to resist buffing stresses incident to service condi-

tions, which sills are spaced apart beyond the bolsters to receive between them standard types of draft rigging now approved by the Master Car Builders' Association.

The principal object sought to be attained 55 is the simplification of the construction of such cars in-so-far as the anchoring against longitudinal movement is concerned.

In the drawings the invention is illustrated as applied to a tank car to which class 60 of cars it is particularly adapted. Heretofore it has been customary to add one or more elements to the structure of tank cars in order to prevent movement of the tank relative to the underframe; either head-blocks have been fixed to the underframe and disposed for engaging the opposite ends 65 of the tank, or fixtures of various kinds have been attached to the tank and underframe intermediate the ends of the tank, for accomplishing the same result. With the present invention, however, all necessity for these additional elements is eliminated.

In the common construction of tank cars the draft gear is supported between a pair 75 of draft sills and the forward and rear followers of said draft gear are fitted between and limited in their longitudinal movements by front and rear follower stops. These follower stops have been commonly manufactured as independent members and have been riveted to the opposing faces of the draft sills. Heretofore they have had practically no other function than that of limiting the movement of the followers of the 80 draft gear.

This invention provides that the rear follower stops, that is, the follower stops nearest the bolsters, shall be detached from the draft sills and connected to, and depend 85 from or made a part of the tank and thus become an effectual means for preventing or limiting the longitudinal movement of the tank relative to the underframe.

The invention also contemplates the use 95 of the tank anchor as a back stop for the draft gear, thus relieving the center sills of buffing stresses between the end sills and bolsters, which stresses tend to strain the draft sills.

They are, therefore, not connected to the underframe in any way, but, when the tank is in position they project into their appropriate positions between the draft sills and 5 between the bolsters and the adjacent rear followers and, if desired, may contact with portions of the bolsters for positively retaining the tank against longitudinal movement.

10 The members depending from the tank are of such section as to practically fill the space between the draft sills, as will be noted in Fig. 3, and extend downwardly nearly or quite to the lower line of such 15 sills, as will be noted in Fig. 2, thereby providing an anchor at each end of the car well adapted to prevent transverse movement or tipping of the tank on its underframe. The two bolsters with the intermediate 20 portions of the underframe form practically a single projection or abutment between the two appendages from the tank. If no provision is made for the engagement with the bolster, that is to say, if there be an 25 open space between said rear follower stops and the adjacent side of the bolster, it will be apparent that the tank will be allowed a limited longitudinal movement and that, through the contact of the follower stops with 30 the rear followers of the draft gears, the spring and friction devices comprising the draft gears will be utilized to cushion such movement and to prevent an excessive movement. Even when the maximum intended 35 space is eliminated and the follower stops are brought, as nearly as possible, into contact with the bolsters, the springs of the draft gears will serve to cushion what slight movement may be present, should any occur 40 through imperfect workmanship in assembling the parts of the car.

The invention also relates to railway cars in general, and more particularly to cars for carrying a load movable relatively to 45 the car underframing, and in some of its details has special reference to cars for carrying large quantities of fluid, commonly termed "tank cars."

Among other objects of my present invention are the provision of an improved support for the ends of the body or tank, the provision of improved yieldingly resistant abutments for adequately holding the tank in place and at the same time compensating 50 for the hammer-like blows of the liquid in stopping the car, to the end that the tank may neither become loosened from the framing, nor the framing itself disturbed by the 55 blows of the tank; to provide means whereby the springs, frictional members, or other shock absorbing and yieldingly resistant members of the draft gear rigging may be utilized and further proportionately compensate for the movement of the tank; to

provide an improved means for mounting 65 the tank relatively to the framing to the end that it may be most readily removed therefrom, together with such other objects as may hereinafter appear.

It will be understood that the invention is 70 not limited to use in connection with tank cars, but is equally well adapted to use in connection with any and all classes of cars wherein the body portion thereof is independent of the underframe and subject to 75 movement relative thereto.

Referring to the drawings forming part of this specification, the numeral 1 indicates the tank; 2—2 the draft or center sills; 3 the bolster; 4 the draft gear as a whole; 4^a 80 the draft gear yoke; 5 the front follower stops attached to draft sills and 6 the rear follower stops attached to the under side of the tank and forming anchors therefor.

The draft gear is of the conventional form 85 of the well known Cardwell draft gear, which is shown diagrammatically in plan in Fig. 3. The Cardwell gear in addition to the friction blocks A is provided with a transverse spring-supporting rod B, upon 90 each end of which is mounted a spring C, resting between a spring cap D and the draft sills 2. As will be noted in Figs. 2 and 3, the rod B extends entirely through the spaced draft sills 2, and the springs on 95 opposite end portions of said rod constitute the resilient elements of said draft gear.

In the preferred embodiment of the invention, that portion of the bolsters 3 which lies between the draft sills, forms a seat for 100 the rear follower stops or anchors 6 and have smooth transverse faces 7—7 inclined downwardly and slightly forwardly adapted to be engaged by the adjacent similarly inclined faces 8—8 of the rear follower 105 stops 6.

In adapting the old rear follower stops to their new function, as hereinbefore set forth, it has been found desirable to form them into single castings, each comprising 110 a top plate as 9 shaped to fit the under side of the tank or other form of car body, so as to be securely and rigidly fastened there-to one near each end. Integral with and depending from these top plates are suitably 115 ribbed and otherwise reinforced members which form the rear stops 6 constituting the tank anchors. Said stops are disposed in pairs, one of each pair adjacent the inner face of each of the sills 2, and their forward faces are adapted to be engaged by the rear follower of the draft gear in precisely the same manner as if they were fixed to the draft sills as heretofore, there being a clear space left between the stops 6 for the 120 draft gear yoke 4^a to travel from its normal position toward the bolster.

When a car as ordinarily constructed is

subjected to one of the great variety of minor collisions to which cars of all classes are subjected, incident to the coupling of cars together and to other apparent causes, 5 the shock, being received by the underframe, produces a tendency for the underframe to travel longitudinally from beneath the car body. This tendency in the design illustrated herewith is overcome by the engagement 10 of the bolsters with the stops or anchors 6 at both ends of the car as is clearly apparent from the illustration Fig. 1. The shock received by the draft gear at the near end of the car is transferred directly to the 15 adjacent bolster center filler, through the engagement with the adjacent stop 6, thus effectually relieving the tank of the tensile strains to which it might otherwise be subjected. It will be noted that inclined smooth 20 faces 7—7 of the central portions of the bolsters are formed upon extensions 3^a projecting toward the end sills, somewhat beyond the normal line of the bolsters proper and being riveted to the draft sills or center 25 sills, as shown in Fig. 2. This extension is adapted to provide a large rivet area for the rivet connection and permit the use of suitable riveting tools, these extensions 3^a are preferably made hollow and provided with 30 numerous strengthening ribs as shown in Figs. 2 and 3.

In constructing the preferred type of the invention the faces 7 and 8, at opposite ends of the car are made to rest as nearly as possible 35 in contact under normal conditions so that the tank is maintained practically rigid while the car is in actual service upon the road.

It will be apparent from the disclosure in 40 Fig. 6 that when the follower stops as 6^a are designed to have no engagement with the bolsters, the result is slightly different from that described above. With the latter construction a shock received at one end of the 45 underframe will be transferred directly to the tank through the engagement of the draft gear at that end of the underframe with the adjacent stop 6^a, that, in fact, the tank itself will be made to receive the shock. 50 It should be noted that the bolsters, in this design, serve simply to support the weight of the tank, and, aside from the natural friction thus produced, they have no office in preventing the longitudinal relative 55 movement of the tank. This duty devolves entirely upon the draft gears at opposite ends of the underframe. When a car is one of a train a shock received at one end will tend to push the tank toward the opposite 60 end of the underframe. This tendency, however, will be resisted by the engagement of the draft gear at the opposite end of the car with the next succeeding car. This latter engagement will cause the draft gear at that

end of the car to be compressed so as to 65 exert a spring pressure against the adjacent stops 6^a, sufficient to overcome the pressure at the first mentioned end of the car and maintain the tank practically in a fixed relative position.

Tank cars are commonly employed for the transportation of fluids of various kinds, including illuminating oils, fuel oil products, road oils, lard, tar, etc., with all of which it was common to fill the tanks while such 75 commodities are hot. Consequently, the tanks expand in all directions, but because of their length the principal expansion is longitudinal. Because of this expansion it is practically impossible to keep the tank 80 anchors illustrated in surface contact with the bolster fillers, which serve as stops to prevent undue longitudinal shifting of the tank on the underframe due to the contact of the tank anchor lugs with the outer faces 85 of said stops as illustrated near both ends of the underframe at all times. To prevent undue stresses on the tank when thus expanded and the cars are in service while the tank anchoring lugs and stops are separated, the 90 draft gears at each end are positioned as shown with the rear followers of the draft gears in contact with such tank anchors or lugs, thus cushioning the blow which would otherwise be received by the tank shell during 95 buffing when the tank anchoring lugs and stops are abnormally separated due to such expansion of the tank.

What I claim is:

1. In a railway car, an underframe comprising body bolsters, a draft-gear, a car body, resting on said body bolsters and a member connected to said body adapted to receive end thrust of said draft-gear.

2. In a railway car, an underframe comprising body bolsters, a draft-gear, a car body, resting on said body bolsters and a stop depending from the car body and interposed between said draft gear and a part of the underframe.

3. In a railway car, an underframe comprising body bolsters, a draft-gear, a car body, resting on said body bolsters and an anchor on said car body coöperating with said draft gear.

4. In a railway car, an underframe comprising draft sills, a body bolster, a draft gear extending between said sills, a removable car body and a depending stop connected with said body and serving as an anchor 120 for said body between said bolster and draft gear.

5. In a railway car, an underframe comprising sills and bolsters, a car body removably mounted on said bolsters, anchors depending from said body and draft gears co-operating with said anchors.

6. In a railway car, an underframe com-

prising body bolsters, a car body removably mounted on said bolster, a member depending from said body and a draft gear comprising said member.

5 7. In a railway car, an underframe comprising body bolsters, a car body, removably mounted on said bolsters, means depending from said body into the plane of the underframe and a draft gear comprising said 10 means as a back-stop.

8. In a railway car, the combination comprising body bolsters a car body removably mounted on said bolsters and a member depending therefrom adapted to serve as a 15 draft gear back-stop.

9. In a railway car, an underframe, a removable car body, and a back-stop for a draft gear comprising a member depending from said car body.

20 10. In a railway car, an underframe comprising a body bolster, a car body removably mounted thereon, and a draft gear back-stop depending from said car body in contact with said bolster.

25 11. In a railway car, an underframe comprising body bolsters, a car body, removably mounted thereon a draft gear back-stop depending from said body and means adapted to prevent undue shifting of said 30 car body.

35 12. In a railway car, an underframe comprising a body bolster, a car body removably mounted thereon, and draft gear back-stops depending from said body engaging said body bolsters to prevent shifting of said car body.

40 13. In a railway car, the combination comprising an underframe, a removable car body and means to prevent relative longitudinal shifting of said body on said underframe, said means serving as draft gear back-stops.

45 14. In a railway car, an underframe, a bolster comprising a bolster center casting, and a removable car body and a draft gear comprising an interposed anchor member removable with said car body abutting said casting and parts of said draft gear.

50 15. In a railway car, an underframe comprising a bolster, a bolster center casting and a combined draft gear back-stop and a car body anchor in alignment with said casting.

55 16. In a railway car, the combination comprising a car body, a bolster center casting and a draft gear in alignment with said casting, a part of said draft gear serving as an anchor for said car body.

60 17. In a railway car, the combination comprising spaced draft sills a car body freely removable from said draft sills, a bolster, and a draft gear comprising a member removable with said car body.

18. In a railway car, the combination

comprising a removable car body, an underframe comprising a longitudinal and transverse members and draft gears comprising members removable with said car body, said last mentioned members being adapted to impinge said transverse members to prevent 70 shifting of said car body.

19. In a tank car, an underframe comprising body bolsters, spaced draft sills and a removable tank, in combination with tank anchors extending from said tank between 75 said draft sills beyond said bolsters.

20. In a tank car, an underframe comprising a body bolster, spaced draft sills, a draft gear extending between said draft sills, a removable tank, and a tank anchor 80 connected with said tank and extending between said draft sills between the bolster and draft gear.

21. In a railway car, an underframe, a car body thereon, a draft-gear back-stop depending from said body and a bolster member formed with an extension against which said back-stop is adapted to rest.

22. In a railway car, an underframe, a car body thereon, a draft-gear back-stop depending from said body and a bolster member formed with a pair of extensions against which said back-stop is adapted to rest.

23. In a tank car, an underframe including bolsters, center sills and end sills, a tank 95 mounted thereon and tank anchoring means extending between the center sills, and positioned at each end between the bolsters and end sills.

24. In a tank car construction, a metal underframe including bolsters, a metal tank secured thereon by tank bands and adapted to expand longitudinally independently of said underframe and rigid end anchoring means beyond and adapted to depend into 105 contact with each bolster.

25. In a tank car construction, a metal underframe including bolsters, a metal tank secured thereon by tank bands and adapted to expand longitudinally independently of 110 said underframe and rigid end anchoring means beyond and adapted to depend into the plane of said bolsters.

26. A tank car construction comprising center sills, a tank mounted above said sills, 115 a member extending transversely of said sills near the end thereof, and a single anchoring member depending from said tank, near one end thereof, beyond and into alignment with said transverse member and below parts of said sills.

27. A tank car construction comprising a tank support, juxtaposed center sills, a tank mounted above said sills and connected with said sills by tank bands intermediate its ends 125 in combination with anchoring means for said tank beyond said tank support at each end, all so constructed and arranged as to

- anchor said tank against longitudinal shifting and to permit independent expansion of said tank on said sills. 65
28. In a tank car construction, an under-
5 frame including tank supports, a tank
mounted on said tank supports and entirely
disconnected from said underframe except
by tank bands partly surrounding the tank
and anchoring means for said tank depend-
10 ing into the plane of said underframe and
so positioned as to anchor said tank against
longitudinal shifting but allow independent
expansion of said tank with relation to the
underframe. 15
29. In a tank car, an undersupport com-
prising spaced sill members adapted to re-
ceive buffing stresses, a tank mounted there-
on, a bolster filler, below said tank and tank
anchoring means extending between said
20 spaced sills near each end of the tank be-
yond said bolster filler. 25
30. In a tank car, an undersupport com-
prising spaced sill members adapted to re-
ceive buffing stresses, a draft gear operable
partly between said sills near their ends, a
25 tank on said undersupport and tank anchors
adapted to coöperate with said draft gear. 30
31. In a railway car, an underframe, a
draft gear, a car body resting on said un-
derframe and a member connected to and
30 depending from said body adapted to re-
ceive end thrust of said draft gear. 35
32. In a railway car, an underframe in-
cluding a bolster filler, a draft gear, a car
body resting on said underframe and a stop
35 depending from the car body in juxtaposi-
tion to said filler and into alinement with
said draft gear between parts of the under-
frame. 40
33. In a railway car, an underframe, a
draft gear, a car body resting on said under-
frame and an anchor on said car body co-
operating with said draft gear. 45
34. In a railway car, an underframe com-
prising draft sills, a draft gear extending
between said sills, a removable car body and
a stop removable with the car body depend-
ing between said sills, adapted to coöperate
with said draft gear. 50
35. In a railway car, an underframe, a car
body removably mounted thereon, anchors
depending from said body near each end
and draft gears coöperating with said an-
chors. 55
36. In a railway car, an underframe com-
prising draft sills, a car body removably
mounted on said sills, a member depending
from said body and a draft gear normally
in contact with said member. 60
37. In a railway car, an underframe, a
tank removably mounted thereon, means de-
pending from said tank into the plane of
the underframe and a draft gear comprising
said means as back stops. 65
38. In a railway car, the combination com-
prising draft sills, a tank removably mount-
ed on said sills and a member depending
therefrom adapted to serve as a draft gear
back stop. 70
39. In a railway car, an underframe, a re-
movable tank, and a back stop for a draft
gear depending from said tank. 75
40. In a railway car, an underframe com-
prising center sills, a draft gear, a car body
resting on said sills, and a member connect-
ed to said body adapted to receive end thrust
of said draft gear. 80
41. In a railway car, an underframe com-
prising center sills, a draft gear, a car body
resting on said sills and a member connected
to said body adapted to coöperate with said
draft gear. 85
42. In a railway car, an underframe con-
sisting of bolsters and spaced center sills, a
draft gear connected with said sills, a car
body resting above said sills and a stop de-
pending from the car body and interposed
between said draft gear and a bolster. 90
43. In a railway car, an underframe com-
prising draft sills, a draft gear, a car body
resting above said sills and an anchor on
said car body coöperating with said draft
gear. 95
44. In a railway car, an underframe com-
prising draft sills, a body bolster, a draft
gear extending between said sills, a remov-
able car body and a depending stop con-
nected with said body extending down-
wardly between said bolster and draft gear. 100
45. In a railway car, an underframe com-
prising sills and draft gears, a car body re-
movably mounted above said sills, anchors
depending from said body and the draft
gears coöperating with said anchors. 105
46. In a railway car, an underframe com-
prising spaced sills and bolsters, a car body
removably mounted above said sills, a mem-
ber depending from each end of said body
between said sills, and a draft gear co-
operating with said member. 110
47. In a railway car, an underframe com-
prising spaced sills and bolsters, a car body
removably mounted above said sills, anchor
means depending from each end portion of
said body into the plane of the sills and a
115 draft gear in alinement with said depending
anchor, the anchor member being positioned
between the draft gear and the bolster.
48. In a railway car, the combination com-
prising tank supports, a tank removably
mounted on said supports, an anchor mem-
ber depending from each end of said tank
between said supports, means for holding
said anchor members between said supports
and draft gears in the plane of and contact-
ing with said anchor members. 120
49. In a railway car, the combination com-
prising a removable car body, center sills,

- 6 draft gears, anchor members depending from opposite end portions of said car body removable with said car body and contacting with said draft gears, and means for securing the car body on the center sills. 5
50. A tank car construction including a pair of spaced sills, tank supporting saddles connected with said sills, a tank resting on said saddles, tank bands, a ribbed member 10 attached to and depending from the tank near each end between the sills and having a face disposed transversely of and inclined longitudinally of the sills, seats carried between the sills having inclined faces 15 adapted to engage with the inclined face of the ribbed member, said seats having a large rivet area and rivets passing through the portion of the seats forming said rivet area and through the sills. 20
51. A tank car construction including a pair of spaced sills, a tank supported from said sills, tank bands tending to hold said tank in position relative to said sills, a casting depending from said tank between said 25 sills, said casting having a transverse face thereof inclined to the vertical, a member fitting between the sills and riveted thereto and having an inclined face adapted to contact with the inclined face of the casting co- 30 acting therewith and tending to prevent excessive movement between said sills and tank. 35
52. The combination with spaced sills, of a ribbed casting forming a filler between said sills and fastened to the same, said casting having a downwardly and forwardly inclined face, a tank having a hollow anchor depending therefrom between said sills, said anchor having a downwardly and forwardly 40 inclined face contacting with the similarly disposed face of the casting. 45
53. A tank car including a pair of spaced sills, a tank, a cradle secured to the tank and having a hollow anchor depending therefrom between the sills, a sill filler member fastened to said sills and having an inclined face adapted to have said anchor bear against the same, said filler having reinforcing ribs integral with and extending 50 from said face in the direction of strain on the same. 55
54. In a tank car, spaced sills, a tank supported above said sills, tank bands tending to hold said tank to said sills, anchors depending from said tank adjacent the ends thereof, each of said anchors having a face inclined toward the center of the car, seats fitting between the sills and having inclined faces adapted to engage the inclined faces of the anchors. 60
55. The combination with a pair of spaced sills, a pair of spaced filler members fastened to said sills, each of said members having an inclined face facing the adjacent end 65 of the sills, a tank having spaced depending anchors, each of said anchors having an inclined face adapted to engage the inclined face of the adjacent filler member. 70
56. In a tank car, spaced center sills, a tank supported above said sills and held thereon by tank bands, an anchor casting having an inclined face secured to and depending from opposite end portions of the tank, and inclined castings secured between said sills adapted to contact with said anchor 75 castings to prevent excessive movement of the tank relative to said sills. 80
57. In a tank car construction, a metal underframe including bolsters, a metal tank secured thereon by tank bands and adapted to expand longitudinally independently of said underframe, in combination with a casting having an inclined face depending from near each end of the tank, and rigid anchoring means held between parts of the underframe 85 and adapted to contact with said casting depending from the tank. 90
58. In a tank car, spaced center sills, cast stops having inclined faces secured between and to the inner faces of said sills, a tank above said sills and tank anchors connected with opposite end portions of the tank adapted to contact with said stops to prevent excessive longitudinal movement of the tank independently of the sills. 95
59. In a tank car, spaced center sills, cast stops having inclined faces secured between said sills, a tank above said sills and tank anchors having co-acting inclined faces connected with opposite end portions of the 100 tank adapted to co-operate with said stops to prevent excessive longitudinal movement of the tank independently of the sills. 105
60. In a tank car, spaced center sills, cast stops having inclined faces secured between said sills, a tank above said sills, tank anchor castings provided with arcuate upper portions and inclined lower portions depending from the tank near opposite ends thereof between said sills and adapted to contact 110 with the inclined faces of said stops to limit movement of said tank on said sills. 115
61. In a tank car, spaced sills, longitudinally spaced fixed stops connecting both sills, a tank resting above said sills, anchor lugs connected with said tank and depending below the top plane of said stops, the anchor lugs resting in normal surface contact with the sides of said stops next the adjacent ends of said tank and being adapted to move 120 away from said stops when the tank is expanded due to a heated lading. 125
62. In a tank car, spaced longitudinal sills, a tank mounted above said sills, longitudinally spaced stops, each stop being connected to both of said sills, tank anchors secured to and depending from said tank, said tank anchors being positioned to rest in direct

contact with the outer sides of said stops and to be in contact therewith at the normal temperature of said tank and being free to separate from said stops during abnormal expansion of said tank.

- 5 63. In a tank car, spaced longitudinal sills, a tank mounted above said sills, longitudinally spaced stops, each stop being connected to and connecting both of said sills in fixed 10 relation, tank anchors secured to and depending from said tank, said tank anchors being positioned to rest in close contact with

the outer sides of said stops and to be in surface contact therewith at the normal temperature of said tank and being free to separate from said stops during abnormal expansion of said tank. 15

In witness whereof I have hereunto set my hand in the presence of two witnesses.

ALLEN E. OSTRANDER.
